N*1,024.

H. Neidig's Design for Children's Iron Bedsteads.

Patented July, 13, 1858.

FIG. 1.

Heinrich Neidig, of New York, N.Y.
Letters Patent No. 1024, Dated July 13, 1858.

The schedule referred to in these Letters Patent and making part of the same.

To all whom it may concern:

Be it known that I, Heinrich Neidig, of the City, County and State of New York, have produced a new and Ornamental Design for Children's Iron Bedsteads, and I do hereby declare that the following is a full, clear and exact description of the same; reference being had to the accompanying drawings making part of this Specification.

Figure 1. is a side elevation of a Bedstead with the Ornamental designs on the posts represented.

This design consists in forming the upper ends of the head and foot posts of the Childrens Bedsteads, of female busts in Alto. relief, and their central and lower portions, and the middle posts, of such configurations, scroll work and Oak leaf foliage as shall produce a chaste, harmonious and Ornamental design.

The upper portion of the posts A. consists of a female head & bust B. with oak leaves C. and scroll work D. behind and below the same, from which extends downward in an irregular curve or branch, of oak leaves or foliage E. bent at its lower end so as to form a support for a dove F. which is perched upon the same with wings extended, so as to fill the space caused by the enlargement at the part where the horizontal rail G. of the bedstead is fastened. The column portion of the post below the enlarged part, is embellished with oak leaves H. tastefully disposed over the different portions of this lower part of the post, ornamenteally curved sides and scroll work, openings or interstices, and oak leaves enclosed within a panel

Dec. 1024

molding I, pointed above and below, the whole forming an organised configuration of parts harmonious in their character, and in keeping with the object for which they are designed.

The middle posts K, are decorated on their upper flat portions by which they are secured to the horizontal rail, with two divergent branches of foliage J, extending over the horizontal flat portion, their stems terminating beneath the upper points of single oak leaves I, inclosed between the scrolled edges of the said legs or posts K. Beneath the stems of each of these single oak leaves I, is formed a six-cornered angular molding M, with curved sides & pointed above and below, inclosing a corresponding pointed leaf, immediately below which is formed a cluster of oak leaves N, the stems of which are embraced by a circular band or molding formed immediately above a more closely clustered bunch of smaller oak leaves O, whose stems terminate and are lost in the rounded portion of the post or leg to which the castor is attached.

What I claim as new and desire to secure by Letters Patent, is
of displaying and arranging the several decorations over the foot, head
and middle posts of Childrens Iron Bedsteads, as to produce the new and ornamental
design described and represented.
